UNITED STATES PATENT OFFICE.

RAYMOND LESLIE FLOYD, OF CASCADE, IDAHO.

ROTARY SHELF FOR GROCERIES AND THE LIKE.

Application filed July 10, 1923. Serial No. 650,605.

To all whom it may concern:

Be it known that I, RAYMOND L. FLOYD, a citizen of the United States, residing at Cascade, in the county of Valley and State of

5 Idaho, have invented certain new and useful Improvements in Rotary Shelves for Groceries and the like, of which the following is a specification.

This invention relates to new and useful 10 improvements in rotary shelves for groceries or the like, and has for its primary object the provision of such a device wherein articles for sale may be supported thereon, whereby the same may be displayed to the 15 buyers, and wherein said groceries may be removed or placed upon the shelves whenever desired.

A further object is the provision of such 20 a device, wherein an extremely great amount of groceries may be supported within a small area, and wherein the device may be also employed as a storage cabinet for numerous articles.

Yet another object is the provision of a 25 rotary shelf that is extremely simple of construction, and one that will operate effectively under all conditions, the device including relatively few parts, and these correlated in such a manner as to reduce the 30 possibility of disarrangement to a minimum.

The nature and advantages of the invention will be better understood when the following detailed description is read in connection with the accompanying drawings, 35 the invention residing in the construction, combination, and arrangement of parts as claimed.

In the drawings forming part of this application, like numerals of reference indicate similar parts in the several views, and wherein:

Figure 1 is a top plan view of the device.

Figure 2 is a detail vertical transverse cross sectional view, and

45 Figure 3 is a top plan view per se, of the supporting track-way.

Specifically referring to the drawings, my novel device embodies the provision of a vertical standard 5, preferably of piping and 50 being anchored at 6 in a desirable manner to the floor A of the grocery store or other building.

Surrounding said standard 5 is an octagon shaped supporting track-way 7, that includes inner and outer octagon shaped links 55 8 and 9, respectively. At desirable points

upon said inner and outer link sections of the track-way are alined bearings 10, through which extend the shafts 11 of rollers 12.

60 The rotary shelf per se, embodies a lower circular plate 13, that is formed with a central opening, pendent upon which is a flanged collar 14, that has free rotation around the standard 5. Secured at one end 65 between the flanges of said collar 14 in a manner designated at 5 are radiating bars 16, the opposite ends thereof being positioned within a pendent skirt 17 of said plate 13. The said bars 16 adjacent their outer 70 ends are mortised in circular alinement with each other, for the reception of a circular metallic track-way 18, within which engages the rollers 12.

75 In spaced relation from the said circular plate 13, and in spaced relation with each other through the medium of vertical partition shelves 19, are circular shelves 20 of any desirable number, each of which are formed with a relatively large circular 80 opening for providing a storage bin B between said shelves.

85 Surrounding the standard 5 and at a point adjacent its upper end is a flanged collar 21 similar in all respects to the collar 14 before mentioned, and secured at their inner ends between the flanges of said collar preferably by bolts 22 are radiating spokes or bars 23, the outer ends thereof being secured in any desirable manner to the uppermost circular 90 shelf 20.

95 The skirt portion 17 of the plate 13 is circumferentially grooved for the reception of an endless belt 24, and is trained therearound, this endless belt being extended laterally and being in turn trained over a pulley 25 of an electric motor 26.

In view of the above description when considered in conjunction with the accompanying drawings, numerous advantages of 100 a rotary display shelf of the present character will be fully appreciated by those skilled in the art, and even though I have herein set forth the most practical embodiment of the invention with which I am at 105 present familiar, it is nevertheless to be understood that minor changes may be made therein, without departing from the spirit and scope of the invention as claimed.

Having thus described my invention, what 110 I claim as new, and desire to secure by Letters Patent, is:

A rotary display shelf structure comprising a support, a standard mounted thereon, a frame disposed around the standard and spaced therefrom and consisting of sections 5 disposed at angles with relation to each other, said frame being mounted upon the support, rollers journaled upon the frame at the intermediate portions of the angularly disposed sections thereof, a plate journaled 10 upon the standard and having its edge portion disposed over the frame, a superstructure mounted upon the plate, radially disposed bars applied to the under side of the

plate, a U-shaped track carried by the bars and disposed under the plate, the intermediate portion of the track bearing upon the upper sides of the rollers and the side flanges thereof receiving the upper portions 15 of the rollers between them, and an annular skirt member applied to the ends of the bars 20 and having an annular groove adapted to receive a belt for rotating the plate above the support.

In testimony whereof I affix my signature.

RAYMOND LESLIE FLOYD.
